United States Patent Office.

C. W. BRIGGS, OF SPRINGFIELD, MASSACHUSETTS.

Letters Patent No. 81,742, dated September 1, 1868.

IMPROVEMENT IN CHARCOAL-FURNACES.

The Schedule referred to in these Letters Patent and making part of the same.

TO ALL WHOM IT MAY CONCERN:

Be it known that I, C. W. Briggs, of Springfield, Hampden county, Massachusetts, have invented a new and improved Charcoal-Furnace; and I do hereby declare that the following is a full, clear, and exact description thereof, reference being had to the accompanying drawings, making a part of this specification, and to the letters of reference marked thereon, in which

Figure 1 is an elevation of said furnace.

Figure 2 is a plan view of the same, the cover being removed; and in

Figure 3 the left-hand portion shows a part of the sectional view made by the plane passing through the line X X in fig. 1, while the right-hand portion shows a part of the section made by the plane passing through the line X' X' in fig. 2.

My invention consists of a furnace, of cast or sheet metal, for the burning of charcoal or like fuel, which is designed to be inserted in one of the usual openings or kettle-holes in the top of an ordinary cooking-stove, and is so constructed and applied to the stove that the smoke and gas are discharged into the stove, while the heat from the burning fuel can be, in a great measure, utilized, and the supply of draught can be readily regulated. Such furnace, therefore, becomes a convenient substitute for the charcoal-furnaces or brasiers which were formerly used in fireplaces, and affords a ready means of kindling and using sufficient fire for many domestic purposes, without kindling a fire in the stove itself, and thus heating the room, and without consuming much fuel.

The construction of my invention is as follows:

The body, A, of the furnace is a nearly conical vessel, of cast iron, of which the diameter, at the flange, is such that the furnace fits easily into the usual openings in the top of an ordinary stove. At the height of about two inches from the bottom, a flange, F, of about one inch in width, encircles the whole body, and supports the whole furnace when it is applied to the stove. A bail, b, is attached to the furnace by the ears e e. A draught-opening, D, just above the flange F, allows the air-supply to enter the furnace, and can be closed by a small plate, shown as standing upon the flange near by the opening. To conduct the entering air down to the lower part of the furnace, a curved plate, B, is applied to the inside of the furnace, being held in place by small ears a a, so that it can be replaced if injured by the heat. A pin, d, inserted in the side of the furnace, holds the flue-plate B down in its place.

As I have found by trial that the flue-plate B, if terminated at a point near C, will not distribute the draught properly, and that the fire thus supplied with draught will burn up through the fuel only on the side next to the flue-plate, and will usually leave that part of the fuel on the opposite side of the furnace unconsumed, I extend the flue-plate to a point, c', near the centre of the lower part of the furnace. This prolongation of the plate B beyond the point c, so as to place the point of delivering the air-supply near the line of the diameter of the bottom of the furnace, and about one inch above the bottom, I regard as an important feature of my invention.

The point c' may be located a little nearer the point c than the exact central point, but numerous trials with plates of different lengths have shown that a considerable lip or prolongation must be formed upon the plate B to insure a uniform combustion of the charcoal in the furnace. The curved form of the plate B affords an easier air-channel, B', and also allows all the coal to fall to the bottom of the furnace as fast as the lower stratum burns, instead of lodging in angles in the plate.

To prevent the heat from passing directly out into the stove, a plate, C, is carried up from the flange to a point above the top of the opposite air-flue, or as high as possible without coming in contact with the kettles set into the furnace.

The side, G, of the furnace, below the flange, is flattened so as to allow an open end for the smoke-flue C', formed by the plate C. By thus extending the plate C upward, it will be seen that no heat can escape until it has risen to the upper part of the furnace, and come in contact with the articles to be heated.

A cover, c^2 , is provided for closing the top of the furnace when the fire is first kindled or is not in use.

I do not claim a charcoal-furnace having a descending air-flue upon one side, and a diving-flue for the escape of smoke, &c., on the opposite side, as the same is shown and described in the Letters Patent granted to Albert Magee, November 10, 1868; nor do I regard the prolonged lip c^1 as a substitute for the grate shown in combination with said flues in the before-mentioned patent, as such grate fails to deliver the air-supply at such a central point as to secure that uniform combustion of the fuel which I obtain by the prolongation of the plate B.

Having described my invention, what I claim as new therein, is—

1. A charcoal-furnace, surrounded by the flange F, and having a smoke-flue, C', opening beneath the flange, and an air-flue formed by the plate B, prolonged as described, for the purpose of delivering the air-supply at a point near the line of the diameter of the furnace, substantially as specified.

2. In combination with the plate C, forming the smoke-flue, the flanged vessel A, having the side G below the flange flattened, substantially as and for the purpose set forth.

In witness whereof, I have hereunto set my hand, this 27th day of July, A. D. 1868.

C. W. BRIGGS.
